UNITED STATES PATENT OFFICE.

EUGENE E. VANCE, OF AKRON, OHIO.

NECKTIE-STRETCHER.

1,282,150.

Specification of Letters Patent. Patented Oct. 22, 1918.

Application filed December 14, 1917. Serial No. 207,127.

To all whom it may concern:

Be it known that I, EUGENE E. VANCE, a citizen of the United States, residing at Akron, in the county of Summit and State 5 of Ohio, have invented new and useful Improvements in Necktie-Stretchers, of which the following is a specification.

This invention relates to devices adapted to be used for stretching neckties and it consists in the novel features hereinafter described and claimed.

An object of the invention is to provide a device of the character stated which is of simple and durable structure and which may 15 be used to advantage for stretching a tie and for maintaining the same in its desired manufactured shape.

With this object in view the device comprises a casing with means for hanging the 20 same upon a support and having a strip insertible therein. The said strip is rounded at its inner end and the strip may be covered with felt or other suitable soft material and the casing may be lined with a similar material. A block is adapted to coöperate with the said strip and the block is provided at 25 its opposite sides with clamping devices adapted to receive the end portions of the tie and screws are threaded through the block 30 and adapted to bear against the ends of the strip. The intermediate portion of the tie is passed around the strip and when the screws are tightened the tie is stretched along the strip and may be inserted in the 35 casing whereby the tie is held in proper shape.

In the accompanying drawing:—

Figure 1 is a side elevation of the tie stretcher.

40 Fig. 2 is a longitudinal sectional view of the same showing the tie in position therein.

Fig. 3 is a similar view cut on a line at right angles to the view shown in Fig. 2.

45 Fig. 4 is a transverse sectional view of the structure cut on the line 4—4 of Fig. 3.

Fig. 5 is a detailed sectional view of an end portion of the structure.

The tie stretcher comprises a casing 1 which is preferably rectangular in trans- 50 verse section and which is provided at its upper end with an eye 2 adapted to receive a nail or hook whereby the said casing may be suspended or supported. The casing 1 is lined at its inner side with felt or other 55 suitable soft material as indicated at 4.

A block 5 is adapted to be used in conjunction with the casing 1 and a strip 6 is insertible in the casing 1 and adapted to traverse the length thereof. The strip 6 is provided upon its surfaces with soft mate- 60 rial 7 as for instance felt and the upper end of the strip 6 is rounded as at 8. Bars 9 are located at the opposite sides of the block 5 and the said bars are provided at points between their ends with knobs 10. Pins 11 65 pass through the end portions of the bars 9 and springs 12 are interposed between the heads of the pins 11 and the sides of the bars 9 and are under tension with a tendency to hold the said bars toward the sides of the 70 block 5. Screws 13 are threaded through the block 5 and adapted to bear at their ends against the lower end of the strip 6.

When it is desired to stretch a relatively long tie an operator grasps the knob 10 75 and moves the bar 9 away from the sides of the block 5. The end portions of the tie are then inserted under the bars 9 and the knobs 10 are released whereby the springs 12 come into play and force the bars 9 against the 80 tie which is grasped between the said bars and the block 5. The strip 6 is then inserted between the sides of the intermediate portion of the tie and the screws 13 are tightened whereby the strip is moved longitudinally 85 and the tie is stretched along the strip. The strip and tie are then inserted in the casing 1 and are held therein by friction and the casing may be swung up by passing the eye 2 over a nail or any other 90 suitable support. Thus the tie is retained in position upon the strip and within the casing and when removed by reversing the operation above it is in proper shape to be applied to a collar or other article of apparel. When it is desired to stretch a relatively short tie the tie is passed through an opening 3 provided in the strip 6 and when the same is inserted in the casing 1 the tie is moved up in the upper portion of the casing and held in proper shape preparatory 95 to wearing.

From the foregoing description taken in conjunction with the accompanying drawing it will be seen that a tie stretcher of 105 simple and durable structure is provided and that the same may be used to advantage for maintaining a tie in proper condition for wearing about a collar or other article of apparel.

Having described the invention what is claimed is:—

1. A tie stretcher comprising a casing, a strip insertible therein, a block provided at its opposite sides with clamp members adapted to engage the end portions of a tie, the said strip being insertible between the opposite side portions of the tie and screws threaded through the block and adapted to bear against the end of the strip for the purpose of stretching the tie.
2. A tie stretcher comprising a casing, a strip insertible in the casing and provided with an opening adapted to receive the in-

termediate portion of a tie, and means carried by the strip for clamping the tie.

3. A tie stretcher comprising a casing, a strip insertible in the casing and adapted to lie between the opposite side portions of a tie, a block, spring pressed clamps located at the opposite sides of the block and adapted to secure the end portions of the tie against the block and screws threaded through the block and adapted to bear against the end portions of the strip.

25
In testimony whereof I affix my signature.

EUGENE E. VANCE.
